LOOSE-LEAF BOOKLET

Filed Jan. 28, 1922

INVENTOR.

Henry C. Miller

Ira M. Jones
ATTORNEY.

UNITED STATES PATENT OFFICE.

HENRY C. MILLER, OF MILWAUKEE, WISCONSIN.

LOOSE-LEAF BOOKLET.

Application filed January 28, 1922. Serial No. 532,373.

This invention relates to certain new and useful improvements in loose leaf binders of that general type including a pair of binder heads and connecting members for the heads having flexible portions throughout and movable into one or both of the heads to provide for adjustment of the connecting members between the heads.

It is in general the object of the present invention to improve the construction and readiness of operation of loose leaf binders of this type. A more definite object of this invention resides in the provision of means mounted within one binder head and operable on the ends of the flexible post therein to simultaneously move the posts in opposite directions to effect the desired adjustment of the heads with respect to each other.

Another object of this invention resides in the provision of a means for adjusting the capacity of the binder, which is operated independently of the adjustment afforded by the movement of the flexible posts into one of the heads, in such manner that the additional adjusting means may be disposed within the other head to form substantially a magazine of connecting extension post sections which may be projected outwardly of the head as needed to increase the capacity of the binder, or may be retracted into the head to reduce the capacity, and which are interlockingly connected with the head by their disposition therein.

This invention has for a further object to provide plate means slidably mounted within one binder head and connected with the post ends disposed therein for simultaneously moving the post ends in opposite directions to extend or retract the posts.

A still further object of this invention resides in the provision of a readily detachable connection between the post ends and the plate means whereby the binder heads may be readily moved apart by relieving the tension on the posts, disengaging the post ends from the plate means and then manually separating the binder heads.

With the above and other objects in view which will appear as the description proceeds, my invention resides in the novel construction, combination and arrangement of parts substantially as hereinafter described and more particularly defined by the ap-

pended claims, it being understood that such changes in the precise embodiment of the herein disclosed invention may be made as come within the scope of the claims.

In the accompanying drawing I have illustrated one complete example of the physical embodiment of my invention constructed according to the best mode I have so far devised for the practical application of the principles thereof, and in which:

Figure 1 is a view of one binder head of a looseleaf booklet embodying my invention, the hinge cover thereof being in open position to more clearly illustrate details of construction;

Figure 2 is a view of a modified form of binder head, the head cover being broken away to illustrate the interior construction;

Figure 3 is a transverse sectional view taken on the line 3—3 of Figure 2, and

Figure 4 is a fragmentary view of the binder head opposite to that illustrated in Figure 2.

Referring now more particularly to the accompanying drawing, 5 and 6 designate upper and lower binder heads, respectively, between which is clamped a body of leaves 7 by means of flexible post members 8, connected with the upper head 5, in the manner hereinafter described, and movable in the lower head 6 at its end portions. Pivoted to lugs 9 at the ends of the heads, are the upper and lower covers 10 and 11, respectively.

The flexible posts 8 are passed through the usual key hole slots 12 in the end of the body of leaves and each flexible post comprises a series of pivotally connected link members 13 and an end member 14 which is adapted for threaded engagement by a screw threaded stud or tenon 15 formed on one end of a plurality of extension post members 16. Each of these extension post members comprises a pair of hingedly connected sections extensible through openings 17 in the inner wall of the upper binder head 5. One end of each extension section is provided with a socket 18 adapted to receive a closing screw or cap 19 or to provide for the addition of an extra extension section, should it be required. Also the hingedly connected sections may be unscrewed and one or more solid extension post sections

added to the flexible posts in lower binder head to give additional capacity for leaves, then the hinged connected sections are screwed to the one or more solid extension post section inserted between.

To provide access to the interior of head 5 for the manipulation of these sections, the head comprises a body channel plate 20 which is normally closed by a hinged or removable cover 21, cover 21 being readily releasably locked in closed position by suitable latch means 22. In that form of my invention illustrated in Figures 3 and 4, the depth of the recess in head 5 is preferably less than the length of any one extension section link 16 so that when the extension link sections are laid laterally therein and the cover closed, any strain placed on the post will not lengthen the same from the upper binder head, thus providing a reservoir for the extension sections as will be readily apparent.

In that form of my invention illustrated in Figure 1 the binder posts are preferably connected with the upper binder head in any suitable manner and the ends thereof in the head 6 are in the form of socket members to receive removable screws or caps 23, which provide means for attaching the posts to means for extending or retracting the same. In this form of my invention a pair of plates 24 and 25 are slidably mounted in channel 20 and are connected with the opposite ends of a lever 25', medially pivoted in the binder head 6, as at 26, by links 27 and 28, respectively. With this construction it will be obvious that a movement of one plate in one direction will impart a movement to the other in an opposite direction.

Plates 24 and 25 are each provided with one or more recesses 29 in which the heads of caps 23 engage and are held by spring members 30, when cover 21 is closed. Fixed to plate 24 is an internally threaded sleeve or bushing 31 in which is threaded a shaft 32 having its outer portion journaled in a bearing 33 mounted near the adjacent end of the binder head and its extreme outer end squared, as at 34, for the reception of a key (not shown), end 34 being in register with an opening 35 in the binder head end.

In this form of my invention, when it is desired to either add or remove any of the leaves from the binder head, shaft 32 is rotated to move plate 24 outwardly, moving plate 25 in the opposite direction through the medium of links 27 and 28 and lever 25' and consequently releasing the tension of posts 8. Cover 24 is then opened by releasing latches 22 and caps 23 lifted from openings 29, when the binder heads can be moved apart to permit ready manipulation of the leaves.

If it is desired to increase the capacity

of the binder, additional sections may be added by unscrewing the extension sections and inserting either solid or additional pivotally connected links. When it is desired to again clamp the leaves between the binder heads, the ends of the post projecting through openings 16 are moved laterally and caps 23 positioned in openings 29, cover 21 being then closed and screw 32 manipulated to draw plates 24 and 25 inwardly toward pivot 26 and consequently retract the posts.

Referring now more particularly to Figures 2 and 3, the lower binder head 6 comprises a pair of opposed longitudinally channeled plates 36 in which the lower ends of the posts are extensible through elbow shaped guide members 37 registering with openings 38 in the uppermost plate. Elbows 37 afford a continuous smooth surface at the bend of the posts and thus facilitate the extension or retraction thereof. The end of one post is preferably detachably connected with carriage block 40 by pivot 41, the end of the other to carriage block 39, the carriage block 39 being rotatably but non-slidably secured to the inner end of a screw shaft 42 and carriage block 40 being made fast to one end of a channel plate 43 slidably mounted in the lower binder head.

Screw shaft 42 is threaded in an internally threaded sleeve or bushing 44 made fast to the end of plate 43 opposite carriage block 40 and has its outer end squared, as at 45, and in register with an opening (not shown) in the adjacent binder head end for the reception of a manipulating key (not shown). In this form of my invention, a rotation of shaft 42 in a clockwise direction will extend its inner end inwardly from sleeve 44, simultaneously moving plate 43 to the left, with reference to Figure 2, and the post attached to carriage block 39 to the right, thus drawing the posts into the lower binder head to clamp the leaves between the heads. A reverse rotation of screw shaft 42 will extend the posts 8 from the lower binder head, as will be readily obvious, and permit the detachment of the leaves 7.

What I claim as my invention is:

1. A loose leaf binder including a pair of binder heads, a flexible post connected with one head and passed into the other head to extensibly lie therewithin, an elongated plate member slidably mounted in the last mentioned head, said plate being of sufficient width to be guided in said binder head by the side walls thereof, means connecting the portion of the post in the last mentioned head with the plate whereby movement of the plate in one direction will retract the post and movement thereof in the opposite direction will extend the post, and means for moving the plate in said last mentioned head.

2. A loose leaf binder including a pair of binder heads, a flexible post connected with one head and passed into the other head to extensibly lie therewithin, an elongated plate member slidably mounted in the last mentioned head, said plate being of sufficient width to be guided in said binder head by the side walls thereof, means readily detachably connecting the portion 10 of the post in the last mentioned head with the plate whereby movement of the plate in one direction will retract the post and movement thereof in the opposite direction will extend the post, and means for moving 15 the plate in said last mentioned head.
3. A loose leaf binder including a pair of binder heads, a flexible post connected with one head and passed into the other head to extensibly lie therewithin, a plate member 20 slidably mounted in the last mentioned head, said plate having recesses therein, an enlargement on the portion of the post in the last mentioned head for engagement in one of the plate recesses whereby movement 25 of the plate in one direction will retract the post and movement thereof in the opposite direction will extend the post, and means for moving the plate in the last mentioned head.
4. A loose leaf binder including a pair of binder heads, a flexible post connected with one head and passed into the other head to extensibly lie therewithin, a plate member 30 slidably mounted in the last mentioned head, said plate having a recess therein, an enlargement readily detachably carried by the portion of the post in the last mentioned head for engagement in the plate recess whereby movement of the plate in 35 one direction will retract the post and movement thereof in the opposite direction will extend the post, means detachably securing 40 said post enlargement in said recess, and means for moving the plate in the last mentioned head.
5. A loose leaf binder including a pair of binder heads, a flexible post connected with one head and passed into the other head to lie therewithin, an enlargement on 50 the portion of the posts in the last mentioned head, a cover for the last mentioned head, an elongated plate member in the last mentioned head and having a plurality of spaced recesses in which the post enlargement is 55 engageable to make the post fast to said head, and a part carried by the cover for detachably securing the post enlargement in said recess.
6. A loose leaf binder including a pair of 60 binder heads, flexible connecting posts connected with one head and passed into the other head to extensibly lie therewithin, a pair of elongated plates slidably mounted in the last mentioned head, said plates being of sufficient width to be guided in said 65 binder head by the walls thereof, means connecting the portion of the posts in the last mentioned head with the plates, and means for simultaneously moving the plates in opposite directions to retract and extend 70 the posts.
7. A loose leaf binder including a pair of binder heads, flexible connecting posts connected with one head and passed into the other head to extensibly lie therewithin, a 75 pair of plates slidably mounted in the last mentioned head, means connecting the ends of the posts in the last mentioned head with the plates, a medially pivoted lever mounted in the last-mentioned head between said plates, links having their inner ends pivotally connected with the ends of said lever and their outer ends pivoted to the plates whereby a movement of one plate in one direction will cause the other plate to move 80 in a reverse direction, and means for moving one of said plates.
8. A loose leaf binder, including a pair of binder heads, flexible connecting posts connected with one binder head and passed into the other to extensibly lie therewithin, an enlarged head member on the end of each post disposed in the last-mentioned binder head, a pair of elongated plates having a 85 free but substantially snug sliding fit in the last-mentioned binder head, said plates having a plurality of spaced recesses therein for permitting the ready adjustable connecting 90 of the connecting posts therewith by inserting the enlarged head members therein, a lever centrally pivotally mounted in the last-mentioned binder head, a link member pivotally connecting each end of said lever with the adjacent plate, and means for moving one 95 plate to cause coordinated movement of both 100 plates and extend or retract the connecting posts.
9. A loose leaf binder including a pair of binder heads, posts connected with one head and adapted to be adjustably connected 110 with the other head, a pair of plates slidably mounted in the last-mentioned head, means for connecting the ends of the posts in the last-mentioned head with the plates, means forming a leverage connection between said 115 plates whereby movement of one plate will cause a movement of the other in reverse direction, and said means tending to increase and decrease the effective lever arm length 120 between the plates as they are moved to and from each other.
10. A loose leaf binder including a pair of binder heads, posts connected to one head and adapted to be adjustably connected with the other head, a pair of plates slidably mounted in the last said head, adjustable means for connecting the ends of the posts with said plates, a post fixed to the last said head and having movable thereon a pair of oppositely extending arms, links connect- 125 130

ing said plates with said arms, means for moving one of said plates, and said arms and links tending to increase and decrease the effective lever arm length afforded by the arm and link connection between the plates as they are moved toward and away from each other.

11. In a loose-leaf binder including a pair of binder heads adapted to clamp leaves therebetween and posts connected with one head and adapted to be adjustably connected with the other, members mounted in the last-mentioned head and connectible with the portions of the post therein, and means for producing simultaneous movement of said members toward and away from each other including a leverage connection between said members whereby the effective lever arm length increases as the members move toward each other to draw the posts into said last-mentioned head and clamp the leaves between the heads and the effective lever

arm length decreases as the members separate to relieve the pressure on the leaves clamped between the binder heads. 25

12. A loose leaf binder comprising a pair of binder heads adapted to clamp a body of leaves therebetween, posts carried by one head and adjustably connectible with the other head, a pair of plates slidably mounted in the last-mentioned head, means providing an engagement between the posts and plates to lock the heads against movement with respect to each other, means connecting the plates for coordinated movement in opposite directions, and said means including a member pivotally mounted in the last-mentioned head between the plates and link means pivotally connecting the inner end portion of the plates with said member 40 at opposite sides of its pivot.

In testimony whereof I affix my signature.

HENRY C. MILLER.
